US00D856822S

(12) **United States Design Patent** (10) **Patent No.:** **US D856,822 S**
Fath et al. (45) **Date of Patent:** **** Aug. 20, 2019**

(54) **DISPLAY PACKAGE**

- (71) Applicant: **Altria Client Services LLC**,
Richmond, VA (US)
- (72) Inventors: **Scott A. Fath**, Richmond, VA (US);
William J. Bogdiewicz, III,
Richmond, VA (US); **Robert T. Mitten**,
Glen Allen, VA (US); **Ryan Bailey**,
Richmond, VA (US)
- (73) Assignee: **Altria Client Services LLC**,
Richmond, VA (US)
- (**) Term: **15 Years**
- (21) Appl. No.: **29/561,548**
- (22) Filed: **Apr. 18, 2016**

Related U.S. Application Data

- (63) Continuation of application No. 14/998,021, filed on Apr. 17, 2015, now Pat. No. 10,188,143.
